ARMCHAIR

Robert A. Gera, Elmhurst, Ill., assignor to International Furniture, Division of Schnadig Corp., Chicago, Ill., a corporation of Delaware

Application May 16, 1956, Serial No. 41,511

Term of patent 3½ years

(Cl. D15—1)

I claim:

The ornamental design for an armchair, substantially as shown.
